Atty.*

UNITED STATES PATENT OFFICE.

WILLIAM G. RICE, OF PHILADELPHIA, PENNSYLVANIA.

VALVE-GEARING.

SPECIFICATION forming part of Letters Patent No. 679,992, dated August 6, 1901.

Application filed August 29, 1899. Serial No. 728,836. (No model.)

To all whom it may concern:

Be it known that I, WILLIAM G. RICE, of Philadelphia, in the State of Pennsylvania, have invented certain new and useful Improvements in Valve-Gearing, whereof the following is a specification, reference being had to the accompanying drawings.

My invention relates to gearing connective with a governor and a throttle-valve of a steam-engine whereby in the event of the failure of the governor to operate said throttle-valve shall be automatically closed.

It is the object of my invention to provide simple and efficient means to effect the aforementioned result, so arranged as to be conveniently applicable to engines already erected.

My invention also comprehends means whereby my valve-gearing, which is ordinarily automatic in its operation, may be otherwise actuated at the will of the operator.

In the accompanying drawings, Figure 1 is a side elevation of a steam-engine with a convenient embodiment of my invention applied thereto. Fig. 2 shows a detail of construction of the valve-gearing.

In said figures, A is the steam-engine, provided with a steam-supply pipe A', in which is the throttle-valve B. The governor C is of the type wherein the weight c is caused to rise and fall in accordance with the speed of rotation of the shaft c', upon which it is mounted, said shaft c' being actuated in the usual manner by the belted connection c², and said parts being so arranged that the arm d of the lever D is depressed, as shown in full lines in the drawings, during the normal operation of the governor C and is raised to the position indicated by dotted lines when said governor ceases to operate. The cord or

chain E extends from the lever-arm d around the sheaves e to the slide-bar F. Said cord or chain being conveniently supported by sheaves e, said slide-bar F is arranged to reciprocate between the bearing-rollers g, mounted for rotation in the brackets G. In the normal position of the parts said slide-bar F engages the lever H, which is pivotally mounted at h' in the bracket H', and in said position the horizontal arm of the lever H is arranged to uphold the weight I, from which the cord or chain J extends around sheaves

j to the drum B', fixed upon the throttle-valve B.

The arrangement of the parts above described is such that upon failure of the governor C to operate and the consequent movement of the lever-arm d to the position shown in dotted lines in Fig. 1 the slide-bar F will be disengaged from the lever H, which being then free to rotate on its pivot h' permits the weight I to fall to the position shown in dotted lines in said figure, and thus rotate the drum B' in the direction of the arrow and close the valve B.

As a convenient adjunct to the parts above described, whereby the operation of the valve B is automatically effected, I prefer to provide means whereby said valve may be operated at the will of the operator stationed at a distance therefrom. For this purpose an additional cord or chain E' may be connected with the cord or chain E and extended to any desired point, so that traction upon the same will uplift the slide-bar F and free the weight I, with the result above described. I prefer, however, to provide means to operate the slide-bar F and release the weight I electrically, as follows: As shown in Fig. 1, the solenoid K is provided with wiring connections k in circuit with a source of electrical energy, such as a battery K', and provided with a normally open switch K². Said solenoid K is so arranged with respect to the slide-bar F that the establishment of the electric circuit through said solenoid by closure of the switch K² suffices to uplift the slide-bar F and release the lever H and weight I to effect the closure of the valve B, as aforesaid.

A greater range of movement of the slide-bar F may be secured from a given movement of the lever-arm d by the differential sheaves shown in Fig. 2, wherein the cord or chain E², leading directly from the actuating-lever d, is secured upon the smaller sheave e², and the cord E³, leading to the slide-bar, is secured upon the larger sheave e³. Said two sheaves being relatively fixed, it is obvious that a given movement of the cord E² will effect a greater movement of the cord E³.

It is to be noted that the sheave B' may be conveniently secured upon the stem of the

valve B by means of the nut b^2 , which ordinarily serves to retain the hand-wheel B² in operative relation with said stem.

Such a governor as I have illustrated is ordinarily provided with the lever D and certain connections leading therefrom to the internal valves of the engine, so that connection may be conveniently made to said lever in the manner I have illustrated. It is to be understood, however, that connection may be made to any other portion of the governor which will suffice to give motion to the cord E. Therefore I do not desire to limit myself to the precise construction and arrangement of the parts which I have shown and described, as it is obvious that various modifications may be made without departing from the essential features of my invention.

20 I claim—

1. In valve-gearing for an engine, the combination with a movable member of the engine-governor and a throttle-valve in the main supply-pipe of the engine, of mechanism arranged to close said valve, means to normally detain said valve-closing mechanism, mechanism physically connecting said governor member and said detent, arranged to automatically release said valve-closing mechanism, whenever said governor ceases to operate, and an electric circuit, comprising means in coöperative relation with said automatic mechanism, arranged to effect the release of said valve-closing mechanism at the will of the operator, substantially as set forth.

2. In valve-gearing for an engine, the combination with the lever D, operatively connected with the engine-governor C; of the throttle-valve B, in the main supply-pipe of the engine; the stem b' , arranged to be rotated to open and close said valve; the drum B', directly fixed to said valve-stem; the flexible connector J, extending from said drum B', and provided with the weight I, arranged to close said valve B; the lever H,

arranged to support said weight; the slide-bar detent F, normally engaged with said lever; and the flexible connector E, extending from said lever D, to said detent F, arranged to automatically release said lever H, when said governor ceases to operate, and thereby permit the closure of said valve B, solely by the gravitation of said weight I, substantially as set forth. 50

55 3. In valve-gearing for an engine, the combination with the lever D, operatively connected with the engine-governor C; of the arm d, upon said lever D; the detent F; the flexible connector E, extending from said arm d, to said detent F; the lever H, normally engaged by said detent F, and arranged to support the weight I; the throttle-valve B, in the main supply-pipe of the engine, provided with the rotatable valve-stem 60 b' ; the drum B', fixed upon said valve-stem b' ; and the flexible connector J, extending from said weight I, in operative engagement with said drum B', substantially as set forth. 65

4. In valve-gearing for an engine, the combination with the lever D, operatively connected with the engine-governor C; of the detent F; a flexible connector extending from said lever D, to the differential sheave e^2, e^3 ; a flexible connector extending from 70 said sheave to said detent F; the lever H, normally engaged by said detent F, and arranged to support the weight I; the throttle-valve B, in the main supply-pipe of the engine, provided with the rotatable valve-stem 75 b' ; the drum B', fixed upon said valve-stem b' ; and the flexible connector J, extending from said weight I, in operative engagement with said drum B', substantially as set forth. 80

85 In testimony whereof I have signed my name to this specification in the presence of two subscribing witnesses.

WILLIAM G. RICE.
